UNITED STATES PATENT OFFICE.

EPHRAIM W. LIVERMORE, OF BELLINGHAM, WASHINGTON.

EXHIBITING-REEL FOR MUTOSCOPES.

No. 853,811.

Specification of Letters Patent.

Patented May 14, 1907.

Application filed December 11, 1906. Serial No. 347,263.

To all whom it may concern:

Be it known that I, EPHRAIM W. LIVERMORE, a citizen of the United States, and a resident of Bellingham, in the county of 5 Whatcom and State of Washington, have invented a new and Improved Exhibiting-Reel for Mutoscopes, of which the following is a full, clear, and exact description.

This invention relates to exhibiting apparatus, and the object of the invention is to 10 present to the view of an observer a number of specimens of the eggs of fishes or animals of the lower order, and representing the same in successive stages of development, from the 15 egg to the fully developed young creature.

More specifically, the object of the invention is to provide a reel, together with its accessories, which may be readily set up in a 20 mutoscope of ordinary construction and such as are now used for exhibiting a succession of pictures.

The invention consists in the construction and combination of parts to be more fully 25 described hereinafter and particularly set forth in the claims.

Reference is to be had to the accompanying drawings forming a part of this specification, in which similar characters of reference indicate corresponding parts in all the 30 figures.

Figure 1 is a side elevation of a mutoscope, the wall of which is represented as broken away so as to illustrate my exhibiting reel mounted in the interior of the device; Fig. 2 35 is a cross section through the exhibiting reel taken upon an enlarged scale; Fig. 3 is a section on the line 3—3 of Fig. 2 and passing through one of the vials in which the specimens are held; and Fig. 4 is a perspective 40 representing a shoe which is adapted to be slid over the pawl usually found in such machines, for the purpose of attaching the pawl to the particular construction of reel which is used.

45 Referring more particularly to the parts, 1 represents the case of the mutoscope, which case is provided at a suitable point with an opening covered by an eye-shield 2 through which the observer may look in order to see 50 the specimens which are presented to view.

As shown, the machine case is of substantially circular form, and is provided with a fixed horizontal stud 3 upon which there is mounted my reel 4. The construction of 55 this reel is very clearly shown in Figs. 2 and 3; it presents two heads 5 and 6, which are

attached to the end faces of a drum 7, of circular form. In the face of this drum 7 there is formed a longitudinally disposed gutter or channel 8, and this channel affords means 60 for attaching the ends of a band or strip 9, of paper or similar material, which extends continuously around the drum. The ends of this strip are secured in the channel 8 by means of a bar 10 which lies in the bottom of 65 the channel and which is held in position by a suitable fastening device such as the screw 11, as illustrated. As shown most clearly in Figs. 2 and 3, each of the heads 6 projects beyond the lateral surface of the drum, and on 70 its inner side is provided with a plurality of circular pockets 12, and in the bottom of these pockets I provide cushions 13, of de- 75 pressible material, such as rubber. The edge of the head 5 projects beyond the edge 75 of the drum 7 in a similar manner, and at points opposite to the pockets 12, the inner side of this head is provided with notches or recesses 14 which extend in from the edge of the head as indicated.

The specimens are held in a plurality of vials 15 which are mounted in the notches and the pockets 12. In order to facilitate the mounting of the same, these vials are preferably formed each with a projecting 85 boss 16 in its bottom, which is received in one of the pockets 12. Each vial is suitably closed by a suitable stopper 17, and over this stopper there is received a cap 18 having a cushion 19 which seats against the end of the 90 vial, and this cap is held in position by a suitable set screw 20 which passes through the head 5 from the outer side thereof. It should be understood that these vials contain the eggs of fishes, toads or similar creatures, 95 arranged in a series or stages which represent the eggs as they progress through their period of incubation until the perfect creature is formed. In order to preserve the eggs and the creatures, the vials should contain a mixture of formaldehyde and water, in the proportion of about one part of formaldehyde to eighteen parts of water. This mixture will preserve the specimens, but will not change their color or in any way affect their natural 100 appearance.

The reel 4 is rotated in the usual manner by a shaft 21 operated by a crank 22, the said shaft carrying a worm 23 which drives the reel through the medium of a worm wheel 24, 110 in the usual manner. By means of the crank 22, the operation of which is possible after

the insertion of a coin at a suitable point indicated at 25, the specimens may be brought in succession below the observer's eye. Sufficient illumination is produced by an incandescent lamp 26 mounted within the case, and which, in practice, is operated automatically in the usual manner.

The case 1 is provided with a cover 27 having a hinge connection 28 which enables the same to be opened at will for the purpose of replacing or removing the reel or attending to the interior of the device. On the opposite wall 28^a of the case, an outwardly projecting stud 29 is provided, upon which there is rotatably mounted a pawl 30, which has substantially the form shown in Fig. 4. This pawl is usually found in machines of this class, and it consists simply of a wooden block, presenting a flat face 31 disposed toward the reel and a curved rear face, so that an edge 32 is presented which is held against the face of the reel by means of a coiled spring 33, the said spring being attached to an ear 34 which projects up from the upper side of the pawl, as indicated. It should be understood that this pawl 30 is such as is usually found in machines of this class and of a certain type. The general purpose of this pawl is to prevent a backward movement of the reel. It is, however, unsuited to the construction of reel which is necessary in connection with my invention. In order to adapt it for co-operation with the reel 4, I provide a shoe 35, the construction of which is very clearly shown in Fig. 4. This shoe is formed with a body 36, which conforms partly in outline to the pawl 30 and which is adapted to be slid longitudinally over the same, as will be readily understood, the said shoe being retained in position by means of a projecting lip 37 which overhangs the upper extremity of the pawl, and by an inwardly projecting finger 38 which is more or less resilient, and which is adapted to project down over the inner edge 39 of the pawl. The shoe 36 presents a flat side face 40 which is adapted to come against the outer side face of the pawl, and the lower portion of the shoe is formed into a rudimentary shell 41 which in cases the inner end of the pawl. To the lower portion of the shoe there is attached a transverse bar 42, the extremities whereof rest against the edges of the heads 5 and 6. From an inspection of Fig. 3, it will be observed that the edges of these heads are in alignment; that is, the heads are of the same diameter.

By means of the crank 22 the reel will be rotated so as to bring the specimens successively into view, and the portion of the band 9 which lies adjacent to the successive specimens will describe the stage of development which they represent. When the reel has made a complete revolution, the notch or channel 8 will come under the pawl and shoe

36; whereupon, the spring 33 operates to throw the bar 42 into the notch. In this way a further rotation of the reel is prevented. In Fig. 1, the channel 8 is represented in dotted outline, in the position which it assumes when the further movement of the mechanism is about to be arrested. At this time, the upper end or tail of the pawl 30 comes against a stop-pin 43 which is attached to the side wall 28^a of the case. In order to enable the reel 4 to be readily mounted within the case, its drum 7 is provided with a central bore 44 which receives a bushing 45 as illustrated in Fig. 1, and the reel is held in position by means of a split pin 46, which is also illustrated in Fig. 1.

The reel constructed as described, together with the shoe, may be quickly applied to the mechanism of a mutoscope of the type described, the picture reel thereof being first removed, as will be readily understood. In this way, a very interesting and instructive exhibit may be made. The specimens carried in the reel may be readily changed when desired. In this connection, special attention is called to the form of the vials, which facilitates their easy removal from the position in which they are held.

Having thus described my invention, I claim as new and desire to secure by Letters Patent:

1. A reel adapted to be mounted in a mutoscope, in combination with a plurality of vials, and means for securing said vials upon said reel, said vials being adapted to hold specimens in successive stages of development.

2. A reel adapted to be mounted in a mutoscope and having a plurality of pockets, vials received in said pockets, and means for securing said vials therein.

3. A reel adapted to be mounted in a mutoscope and having oppositely disposed heads, one of said heads having recesses therein, vials adapted to be mounted in said recesses and containing specimens in successive stages of development.

4. A reel adapted to be mounted in a mutoscope and having a pair of heads projecting oppositely at their edges, one of said heads having a plurality of pockets formed therein, a plurality of vials mounted in said pockets and adapted to contain specimens in various stages of development, and means carried in one of said heads opposite said pockets for securing said vials in position.

5. In a mutoscope, in combination, a reel comprising a drum and heads projecting beyond the edge thereof, means for retaining vials between said heads and around said drum, a shoe presenting a transversely disposed bar resting on the edges of said heads, means for supporting said bar near the edges of said heads, means for resiliently constraining said bar against said heads, means

whereby said bar may arrest the rotation of said reel in one direction only, and means for rotating said reel.

6. In a mutoscope, in combination, a reel presenting heads with notches in the edges thereof, a pivotally mounted pawl having a shoe with a bar resting on said edges, a spring impelling said pawl to hold said bar against the edges of said heads, means for rotating said reel, said bar being adapted to engage said notches and to prevent the rotation of said reel in one direction.

7. In a mutoscope, in combination, a rotatable reel presenting substantially circular heads, means for supporting vials between said heads and near the edges thereof, a pawl pivotally mounted adjacent to said reel, a shoe adapted to be attached to said pawl and having means for engaging said reel, said

heads having notches to engage said shoe to prevent the rotation of said reel in one direction, and means for rotating said reel.

8. In a mutoscope, in combination, a reel presenting substantially circular heads having notches in the edges thereof, means for supporting vials near the edges of said heads, a pawl pivotally mounted in said reel, a removable shoe adapted to be attached to said pawl and having a transverse bar, means for holding said bar in engagement with said heads, and means for rotating said reel.

In testimony whereof I have singed my name to this specification in the presence of two subscribing witnesses.

EPHRAIM W. LIVERMORE.
